UNITED STATES PATENT OFFICE.

BENJAMIN D. BRANTLEY, OF BLACKSHEAR, GEORGIA, ASSIGNOR TO THE
A. P. BRANTLEY COMPANY, OF BLACKSHEAR, GEORGIA, A CORPORA-
TION OF GEORGIA.

METHOD OF GINNING COTTON.

SPECIFICATION forming part of Letters Patent No. 747,315, dated December 15, 1903.

Application filed October 8, 1903. Serial No. 176,295. (No model.)

To all whom it may concern:

Be it known that I, BENJAMIN D. BRANTLEY, a citizen of the United States, residing at Blackshear, in the county of Pierce and State 5 of Georgia, have invented certain new and useful Improvements in Methods of Ginning Cotton; and I do declare the following to be a full, clear, and exact description of the invention, such as will enable others skilled in 10 the art to which it appertains to make and use the same.

My invention relates to a method of ginning cotton, and has for its object to prevent "air-drying" during the operation of ginning 15 and to preserve the natural properties and characteristics of the cotton fiber, of which the cotton is usually deprived during the ginning operation.

In passing the seed-cotton through the gins 20 the cotton fiber is more or less under the influence of air-currents created by the rapid rotation of the members of the gin which separate the fibers from the seeds, and where the cotton is impelled or moved from the gins to 25 the compress by forced air-currents or suction the cotton fibers come still farther under the influence of air-currents, all of which are calculated to cause air-drying, and this to a greater or less extent deprives the cotton 30 fibers of their natural properties and characteristics. This is particularly so with "sea-island" or long-staple cotton. This species of cotton naturally possesses great length, strength, fineness, smoothness, and 35 luster or silkiness of fiber, which properties or characteristics under the ginning operation as ordinarily practiced are more or less impaired, and when thus impaired the fibers become somewhat fluffy and brittle and lose 40 some of their silkiness and luster, which impairment is due to the air-drying incident to the conditions prevailing during the ginning operation.

With the view of preserving the natural 45 properties and characteristics and preventing the impairment mentioned, especially so in sea-island or long-staple cotton, my invention consists in subjecting the cotton to an artificially-humidified atmosphere during the 50 ginning operation, whereby, as I have discov-

ered, the air-drying of the cotton fibers is prevented to such an extent that the natural strength, fineness, smoothness, and luster or silkiness of the fibers are preserved and the fibers are prevented from becoming harsh, 55 brittle, and fluffy.

In carrying out my invention the ginning-room is equipped with humidifiers of any well-known approved pattern or type, located at appropriate or convenient points and of 60 the number desired, so as to artificially humidify the atmosphere of the room in which the gins are located, so that the cotton fibers during the ginning operation will be subjected to or be under the influence of this artificially-created humidified atmosphere, whereby the air-drying incident to the ginning operation as ordinarily conducted is prevented to such an extent that the natural properties or characteristics of the fibers are 65 protected against injury or impairment and retained by the fibers, so that the cotton after being ginned will possess the strength, fineness, softness, and luster or silkiness which are distinguishing characteristics of sea-island 70 or long-staple cotton. The degree of humidity given to the atmosphere may vary without departing from the spirit of my invention and the discovery which I have made, and a satisfactory degree of humidity, ascertained by 75 practicing my invention, may be from 60° to 70°, and I have found that four humidifiers that will give that degree of humidity for an approximate area of fifty-five thousand square feet will produce most satisfactory 80 results. These figures, however, are given merely for purposes of illustration and without the intent of being limited thereto in practicing my invention. I have also observed that as incident to this method the cotton is 85 prevented from losing any undue weight during the ginning operation.

While the invention is particularly beneficial in the ginning of sea-island or long-staple cotton, yet I am not to be restricted in its 90 application to the ginning of sea-island or long-staple cotton where beneficial results may be obtained by its application to the ginning of short-staple or "upland" cotton, as the invention lies in the discovery that the 95 100

beneficial results mentioned will be obtained in conducting the ginning operation in an artificially-created humidified atmosphere, so that the cotton while undergoing the ginning operation will be under the influence of an artificially-created humidified atmosphere.

Having described my invention and set forth its merits, what I claim is—

The method of ginning cotton consisting in creating an artificially-humidified atmos-

phere and subjecting the cotton during the ginning operation to the influence of such created atmosphere, substantially as described.

In testimony whereof I affix my signature in presence of two witnesses.

BENJAMIN D. BRANTLEY.
